UNITED STATES PATENT OFFICE.

THOMAS BENNINGFIELD, OF ENGLEWOOD, KANSAS.

CLOTHES-LINE POST.

992,842.

Specification of Letters Patent. Patented May 23, 1911.

Application filed February 11, 1910. Serial No. 543,285.

To all whom it may concern:

Be it known that I, THOMAS BENNINGFIELD, a citizen of the United States, residing at Englewood, in the county of Clark 5 and State of Kansas, have invented certain new and useful Improvements in Clothes-Line Posts, of which the following is a specification.

This invention relates to improvements in 10 clothes line posts and embraces the construction of an improved post capable of being vertically adjusted so that the clothes can be elevated above the dust zone developed by passing vehicles.

15 One of the objects of the invention is the construction of a simple and inexpensively constructed post comprising a supporting member and a telescopic member and means whereby the telescopic member may be elevated on the supporting member.

20 With the above and other objects in view the invention comprises certain combinations, constructions and arrangements of parts, clearly described in the following 25 specification and clearly illustrated in the accompanying drawings, in which—

Figure 1 is a side elevation showing the device in use, Fig. 2 is a detail view, partly in section of the gearing for elevating the 30 telescopic member, Fig. 3 is a detail sectional view of the post, and Fig. 4 is a detail view of a wire separating member. Fig. 5 is a top plan view of the post.

Referring to the accompanying drawings, 35 which are merely illustrative of the invention 1 denotes the supporting member, which is formed hollow and has its lower end inserted in the ground. The member 1 is braced by means of wire braces 2. On the 40 upper end of member 1, a bracket 3, is secured for the purpose of supporting a gear wheel 4, which rotates within said bracket 3, and in a slot formed in the upper end of member 1.

45 A member 5 is telescopically inserted in the member 1, and said member 5 is formed U-shaped and is provided with a series of notches 6, secured between the legs of said member 5, and adapted to mesh with the 50 teeth of the gear 4.

The gear wheel 4 is held in fixed position

by means of a pawl 7, secured between the brackets 3 and is operated by a handle 8. By rotating the gear 4 the movable member 5 may be alternately elevated or lowered. 55

On the upper end of the movable post member 5 a bracket 9, is provided to which a winding reel 10, is secured, said reel being provided with a ratchet wheel 11 and held in fixed position by a pawl 12. The reel 10 is 60 operated by a handle 13 forming a shaft therefor. The movable post section 5 also carries a guide wheel 14, pivoted between the sides of said section, and a guide arm 15 projecting forwardly of said wheel 14. Two 65 clothes line wires or ropes 16 and 17 are passed through the aperture in the upper end of the guide arm 15 and the ends of said wires or ropes are connected to the reel 10, after passing over the guide wheel 14. 70

In order to space the wires or ropes 16 and 17 apart from each other a device is used which comprises a bar 18 having slots 19 formed in its ends. A series of pins 20 are secured to the slotted ends of the bar 18 so as 75 to hold the ropes or wires 16 and 17 various distances apart from each other.

By means of the improved device it is possible for a person to readily lower the clothes line wires or ropes so as to be easily 80 reached from the ground, without any support, and to readily elevate the lines when loaded with clothes so that they will be brought above the dust zone created by passing vehicles. By means of the reel 10 85 the clothes wires or ropes may be readily tightened without trouble.

Having described my invention I claim:—

In a clothes line device, a supporting pipe, 90 a clothes line holding pipe slidable thereon, means for moving the slidable pipe on the supporting pipe, a guide wheel on the upper end of the slidable pipe, a guide arm on the 95 slidable pipe, and means carried by the slid- able pipe for holding the clothes lines apart.

In testimony whereof I affix my signature in presence of two witnesses.

THOMAS BENNINGFIELD,

Witnesses:

THEO. STOOP,

JAMES ALLEN.
